UNITED STATES PATENT OFFICE.

JOHN D. SHARPLES AND THOMAS CROWE, OF TAFTVILLE, CONNECTICUT, ASSIGNEES TO
OLD COLONY MACHINE COMPANY, OF NEW BEDFORD, MASSACHUSETTS, A CORPOR-
ATION OF MASSACHUSETTS.

BOBBIN-STRIPPING MACHINE.

1,289,939.

Specification of Letters Patent. Patented Dec. 31, 1918.

Application filed February 18, 1918. Serial No. 217,737.

To all whom it may concern:

Be it known that we, JOHN D. SHARPLES and THOMAS CROWE, both citizens of the United States, and residents of Taftville, county of New London, and State of Connecticut, have invented an Improved Bobbin-Stripping Machine, of which the following is a specification, reference being had to the accompanying drawings, forming part thereof.

The present invention relates to an improved machine in which spent bobbins having on their shafts tail ends of roving or yarn can be mechanically fed forward to a device effective to sever the coils of said tail ends of roving or yarn without injury to the heads or shafts of the bobbins.

One of the objects of this invention is to provide a machine having a roving or yarn severing implement from which the bobbin, in its feeding movement, is always positively spaced, provision being made to bring the coils of roving or yarn to position to be severed.

Another object of the invention is to provide a novel means to guard the severing implement in order to avoid injury to the operative.

Another object of the invention is to provide a novel guide or guard for determining the approach of the bobbin head or shaft to the roving or yarn severing implement.

Other objects of the invention will appear from the following description.

The invention consists in the construction of the yarn severing implement and its guard.

The invention also consists in the fixed means for engaging the coils of roving or yarn and so separating them from the shaft of the bobbin that said coils may be subjected to the shearing cut of a suitable severing implement without possibility of injury to said bobbin.

The invention also consists in such other novel features of construction and combination of parts as shall hereinafter be more fully described and pointed out in the claims.

Figure 1, represents the improved machine in side elevation.

Fig. 2, represents a plan view of parts of the machine.

Fig. 3, represents an enlarged vertical sec-

tional view of parts thereof taken on line 3—3 Fig. 2.

55

Fig. 4, represents an enlarged sectional view of parts of the machine as taken on line 4—4 Fig. 3.

Fig. 5, represents an end view of Fig. 6, showing a detail of the guard for the severing implement.

Fig. 6, represents a side elevation of Fig. 5.

Fig. 7, represents a side view of the quill or sleeve carrying the yarn or roving lifting device.

Fig. 8, represents an end view of Fig. 7 to show the yarn or roving lifting device.

Fig. 9, represents an enlarged sectional view taken on line 9—9 Fig. 4, to show the guard swung to expose the severing implement and the yarn coils on a bobbin shaft riding up the lifting device to the severing implement.

Similar characters of reference designate 75 corresponding parts throughout.

In carrying this invention into practice we construct a machine having a runway constituted by the parallel side members 11, 11 spaced apart and suitably braced and supported at a convenient height. The bobbin carrying belt 12 extends through said runway and is mounted on the pulleys 13 and 14 of which pulley 14 is mounted on a shaft which has the belt pulley 15 driven by belt 16 from the pulley 17. The bobbin carrying or feeding belt 12 has the outstanding members 18, 18 which engage and move forward bobbins placed on said belt 12 in a suitable position. Provision is made to yieldingly support a portion of the belt 12 at or about the point at which the yarn severing operation occurs by means of the roller 19 journaled on a shaft of the counterweighted arm 20 which latter is pivotally sustained between brackets 90 21, 21 depending from the side members 11, 11. At a suitable point in the length of said runway is located the downwardly inclined dropper plate 22 which has members secured to said side members 11, 11. The office of this dropper plate 22 is to guide downward the bobbins passing therebeneath on said belt 12 to overcome the lifting action of roll 19 on belt 12.

Mounted on or in the side frame members 105 11, 11 at points approximately adjacent the

11, 11 at points approximately adjacent the

point at which belt 12 is yieldingly sustained by roller 19 are the bearings 23 and 24 in which respectively the quills or sleeves 25 and 26 are secured. Quill 25 has at its inner 5 end the disk 27 having at its periphery the clearance 28 the lower portion of which has the inclined yarn lifting edge 29 terminating in the yarn engaging point 30 which meets the peripheral curve or guard edge 31 10 of said disk 27. Quill or sleeve 26 has at its inner end the bearing 32 having the stop pin 33. On this bearing 32 is rotatably received the collar 34 of the guard shell or casing 36 having the opening 37 in its peripheral wall 15 and the counterweighted arm 38. Collar 34 has the slot 35 through which stop pin 33 extends whereby the swinging of the guard casing 36 on said bearing 32 is limited by the length of said slot 35. Disk 27 of quill 25 20 may fit slightly within the peripheral wall of the guard shell or casing 36 and constitute a closure therefor.

Journalized in the bores of the quills or sleeves 25 and 26 is the cutter shaft 39 having the belt pulley 40 and the cutter disk or element 41 which latter is contained within the guard shell 36 and rotates approximately in contact with the disk 27. This cutter element 41 has a diameter somewhat 30 less than the disk 27 or, at least, the curve 31 of point 30 extends beyond the radius of the cutter element 41 and guards the approach to the edge of said cutter element.

On the quills or sleeves 25 and 26 are adjusted and secured the conical guard members 42, 42 which, preferably, are spaced apart a distance which will permit the passage therebetween of the head *h* of a bobbin shaft *s* without permitting said bobbin head 35 to be raised by the counterweighted roll 19 into an injurious contact with the mechanism located between said guards 42, 42. At the same time the conical shape of these guards 42, 42 will not unduly resist the passage of 40 the head *h* of a bobbin and, after the passage of said head *h*, will permit the bobbin shaft *s*, because of its small diameter, to be raised by roll 19 into contact with the curved edge 31 of the yarn engaging point 30 of member 27.

Pulley 17 is on the shaft 43 which has also the pulley 44 driven by belt 45 from the pulley 46 of the main shaft 47. This latter shaft is operated in any usual manner and 55 has the pulley 48 which operates the belt 49 whereby the pulley 40 of cutter shaft 39 is driven. Any other suitable driving mechanism may however be substituted for that shown.

60 Normally guard shell or casing 36 will be swung by its weight 38 to about the position shown in Fig. 5, and the point 30 of member 27 with the adjacent portion of the cutter disk 41 will be guarded somewhat thereby to 65 prevent injury to an operative's hand.

When a bobbin advances with the belt 12 its head *h* will pass beneath the dropper plate or guide 22 and will be guided thereby downward against the resistance of roll 19. After passing beyond the lower end of said dropper plate 22 the bobbin head *h* will be raised by roll 19 and will be received between the conical guards 42, 42 which, as stated above, will limit the upward movement of said bobbin head, such upward movement of the bobbin head will however be sufficient to enable it, in its further advancing movement, to engage weight 38 of the guard casing or shell 36 and thereby effect the swinging of said shell 36 approximately as shown in Fig. 9, and this shell 36 will be maintained substantially in such position by the shaft *s* of the bobbin passing beneath said weight arm 38. As the bobbin shaft rises between the conical guards 42, 42, 85 said shaft will contact with the curved edge 31 of member 27 adjacent the point 30 and will ride against said edge without injury to said bobbin; the point 30 will engage between the coils *c*, *c* of roving or yarn on the 90 bobbin and will act as a wedge to stretch or lift said coils away from the bobbin shaft whereby said coils will ride up the inclined edge 29 of said member 27 sufficiently to bring said coils against the severing edge of 95 the rotary cutter disk 41 which owing to its shearing cutting action effectually severs said coils *c*, *c* which will then drop from the shaft of the bobbin without leaving any material amount of lint or fluff.

Having thus described our invention we claim as new and desire to secure by Letters Patent:

1. A bobbin stripping machine comprising means to feed forward bobbins having tail ends of roving or yarn, a yarn severing element stationed above the path of said bobbins, means to limit the approach of a bobbin to said severing means, and a fixed means which takes under the coils of roving 105 or yarn on said bobbin and raises said coils into position to be severed by said element.

2. A bobbin stripping machine comprising means to feed forward bobbins having tail ends of roving or yarn, a yarn severing 110 disk rotatably mounted above the path of said bobbins, means to limit the approach of a bobbin to the edge of said disk, and a fixed means for taking under coils of said roving or yarn on said bobbin and raising 115 said coils into position to be severed by the peripheral edge of said disk.

3. A bobbin stripping machine comprising a pair of coöperating elements of which one acts to take under and raise yarn from 125 a bobbin and the other acts to sever the yarn when so raised, and mechanism to effect a relative movement between a bobbin and said elements.

4. A bobbin stripping machine comprising 130

- ing means to feed forward bobbins having tail ends of roving or yarn, a wedge element fixed in position to take under coils of yarn on a bobbin so fed forward to raise said coils 5 from said bobbin, a yarn severing implement having a cutting edge stationed adjacent said wedge implement, and means to operate said severing element to effect a shearing cut on yarn raised by said wedge.
- 10 5. A bobbin stripping machine comprising yielding means to feed forward bobbins having tail ends of roving or yarn, a rotary disk cutter stationed above the path of said bobbins, and a yarn engaging implement extending in a fixed position adjacent the edge 15 of said cutter to take under and raise said yarn to a severing position.
6. A bobbin stripping machine comprising yielding means to feed forward bobbins 20 having tail ends of roving or yarn, a shaft rotatably mounted above said bobbin feeding means, a disk cutter on said shaft, and a fixed implement extending downward beside said cutter and beyond the cutting edge 25 thereof to bear against the bobbin and to take under and raise coils of roving thereon to contact with said cutting edge.
7. A bobbin stripping machine comprising yielding means to feed forward bobbins 30 having tail ends of roving or yarn, a shaft rotatably mounted above said bobbin feeding means, a disk cutter on said shaft, and a counterweighted swing guard for the edge of said disk.
- 35 8. A bobbin stripping machine comprising yielding means to feed forward bobbins having tail ends of roving or yarn, a shaft rotatably mounted above said bobbin feeding means, a disk cutter on said shaft, and a guard for the edge of said disk pivotally 40 mounted and having means normally to maintain said guard between said cutter and the path of the bobbins.
9. A bobbin stripping machine comprising yielding means to feed forward bobbins 45 having tail ends of roving or yarn, a shaft rotatably mounted above said bobbin feeding means, a disk cutter on said shaft, and a guard mounted to swing on the axis of said disk and having an edge to partially embrace 50 said disk and an arm to swing said guard, said arm adapted to be actuated by an advancing bobbin to swing said guard to an open position.
10. A bobbin stripping machine comprising yielding means to feed forward bobbins 55 having tail ends of roving or yarn, a pair of members mounted above said bobbin feeding means, conical bobbin guards adjustably mounted on said members, one of said members having a depending yarn engaging element having an inclined upper edge, the other of said members having an annular pivoted guard having a depending weight arm, a shaft rotatably mounted in said members and having a disk cutter located between said yarn engaging element and said guard, and means to drive said cutter shaft. 60
